UNITED STATES PATENT OFFICE

166,085

CARPET UNDERLINER

Charles Lachman, Bryn Mawr, Pa.

Application July 18, 1949, Serial No. 3,979

Term of patent 14 years

(Cl. D92—4)

To all whom it may concern:

Be it known that I, Charles Lachman, a citizen of the United States of America, residing at Bryn Mawr, in the county of Montgomery and State of Pennsylvania, have invented a new, original, and ornamental Design for a Carpet Underliner, of which the following is a specification, reference being had to the accompanying drawing, forming part thereof.

I claim:

The ornamental design for a carpet underliner, as shown.

CHARLES LACHMAN.
